CLAIM

The ornamental design for a dining chair, as shown and described.

DESCRIPTION

FIG. 1 is a front, bottom and right perspective view of the dining chair, showing my new design;

FIG. 2 is a rear, top and left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded view thereof;

FIG. 10 is an exploded view thereof; wherein the seat and the legs are shown separately;

FIG. 11 is another exploded view thereof; wherein the seat and the telescoping legs are shown separately;

FIG. 12 is an enlarged detail view of area 12 in FIG. 1;

FIG. 13 is an enlarged detail view of area 13 in FIG. 1;

FIG. 14 is an enlarged detail view of area 14 in FIG. 1;

FIG. 15 is an enlarged detail view of area 15 in FIG. 1; and,

FIG. 16 is an enlarged detail view of area 16 in FIG. 1.

The broken lines in the drawings illustrate the portions of the dining chair, which form no part of the claimed design.

The dash-dot-dash broken lines in FIGS. 1, 12, 13, 14, 15 and 16 show the boundaries of the enlargements shown in FIGS. 12, 13, 14, 15 and 16, and form no part of the claimed design.
